WALL-MOUNTED CLOTHES-DRYING RACK
OR SIMILAR ARTICLE

Nathan W. Roop, Columbus, Ohio, assignor to Columbus Plastic Products, Inc., Columbus,
Ohio, a corporation of Ohio

Application May 6, 1950, Serial No. 9,764

Term of patent 14 years

(Cl. D33—8)

To all whom it may concern:

Be it known that I, Nathan W. Roop, a citizen of the United States, residing at Columbus, in the county of Franklin and State of Ohio, have invented a new, original, and ornamental Design for a Wall-Mounted Clothes-Drying Rack or Similar Article, of which the following is a specification, reference being had to the accompanying drawing, forming a part thereof.

Fig. 1 is a perspective view of a wall-mounted clothes-drying rack or similar article, showing my new design with the clothes-supporting arms of the rack extending outwardly from the body thereof in fan-shape;

Fig. 2 is a similar view showing the arms of the rack in their retracted positions within the body thereof;

Fig. 3 is a similar view of the rack looking toward the opposite end thereof; and

Fig. 4 is a perspective view of the rack with the clothes-supporting arms occupying their extended positions in vertically superposed relation.

I claim:

The ornamental design for a wall mounted clothes-drying rack or similar article, substantially as shown.

NATHAN W. ROOP.
